APPARATUS FOR REPLACING CATHODES

Karl Krause, Berlin, Germany

Application May 13, 1940, Serial No. 334,964
In Germany February 17, 1939

3 Claims. (Cl. 250—27.5)

The present invention relates to electric discharge devices and more specifically pertains to means for replacing cathodes of electrical discharge tubes without disturbing the pressure therein.

In a prior arrangement a rod-shaped cathode carrier is fitted in a guide member so that the rod can be easily removed therein. The guide member is sealed with respect to an insulating jacket or housing and extends into the discharge tube formed by the housing. The housing is sealed externally by a packing on the outer end of the guide member. The replacement of the cathodes is effected in such a manner that when the packing is loosened, the cathode rod may be withdrawn and provided with a new cathode and re-inserted in the guide member whereupon the packing is tightened. By such an arrangement cathodes can be replaced in a simple manner in a comparatively short period without dismantling parts of the tube and without the operation of the discharge apparatus being interrupted for a long period. Such an arrangement however provides the disadvantage that the vacuum of the tube is disturbed or lost during the replacement of the cathode.

The present invention, which is based on the fundamental principle of replacing the cathode includes an arrangement wherein the cathode supporting rod is fitted in a guide member and is easily movable therein. The present invention however avoids the disadvantage hereinabove referred to and renders possible the replacement of cathodes without affecting the pressure of the electrical discharge apparatus. The means and the operation of the invention is hereinafter described with reference to the accompanying drawing.

The single figure of the drawing is a sectional view of apparatus embodying the invention.

A tube 3 is secured at its lower end to a solid spherical member 4. The tube 3 may be attached to the ball 4 in a suitable manner such as by threads 3a. The ball 4 is provided in the direction of the guide member 3 with an opening for the passage of a cathode supporting rod 1. The spherical member 4 is surrounded by a two-part casing or housing 9 in which the ball is tightly fitted. The lower part 5 of the casing is provided with two sockets 6 and 8. The socket 6 forms an extension of the guiding means for the cathode supporting rod 1 in the direction of the tube 3 and the socket 6 communicates with the interior of a discharge tube 1. The other socket 8

is arranged laterally of the socket 6 and serves for replacing the cathodes.

The upper part of the casing or housing 9 is designed as a cap nut and is secured to the lower part 5 in any suitable manner such as by means of threads 9a and even welded to the part 5. A cylindrical resilient member such as a bellows 10 is preferably welded to the casing or housing 9. The other end of the bellows 10 is connected in a vacuum-tight manner to the upper part of the tube 3 by means of a closure disc 11 which surrounds the tube 3 and is sealed with respect thereto as indicated at 11a.

The guide member or tube 3 is closed at the upper end thereof by a conical member 14 provided with a hand wheel 13. The conical member 14 is provided with an extension providing a threaded spindle 15 engaging threads of the hollow cathode supporting rod 1 so that when the hand wheel 13 is rotated the cathode carrier 1 is moved in the guide member 3.

If a cathode replacement is to be made the hollow cathode supporting rod 1 is moved from the position indicated in dotted lines to the position shown in full lines by turning the hand wheel 13. The guide member 3 with the cathode supporting rod 1 and including the yielding resilient member 10 are now swung out of the axis of the socket 6 into the axis of the socket 8. For this purpose a slot 16 is provided in the casing or housing 9. By the movement of the threaded spindle 15 the cathode supporting rod 1 is inserted in the socket 8. After loosening the plate 12, the used cathode 2 is removed and replaced by a new one. In reverse order, the cathode supporting rod is reinserted with a new cathode 2 in the guide socket 6 and moved at a suitable distance from the anode 17.

By moving the vacuum-tight connected resilient member 10 it is therefore possible to replace cathodes without destroying the vacuum of the discharge apparatus.

While the invention has been described with reference to specific structural details it will be appreciated that changes may be made therein by those skilled in the art. Such changes may be made without departing from the spirit and scope of the invention as set forth in the appended claims.

I claim:

1. Apparatus for removing and replacing a cathode of an electrical discharge tube having a sealed housing comprising, a spherical-shaped casing having a socket sealed with respect to said housing, a spherical member fitting tightly with-

in said casing, said spherical member having an opening therethrough, a guide member secured to said spherical member and extending therefrom in alignment with said opening, a cathode 5 supporting rod fitting within said guide member and movable therein, a second socket carried by said casing arranged at an angle with respect to the first socket, and a resilient member sealing said casing with respect to said guide member.

10 2. Apparatus for removing and replacing a cathode of an electrical discharge tube having a sealed housing comprising, a spherical-shaped casing having a socket sealed with respect to said housing, a spherical member fitting tightly within said casing, said spherical member having an opening therethrough, a guide member secured to said spherical member and extending therefrom in alignment with said opening, a cathode 15 supporting rod fitting within said guide member and movable therein, said casing having an opening 20 and movable therein, said casing having an opening therein arranged at an angle with respect to

said socket and normally covered by said spherical member, and a flexible bellows sealing said casing with respect to said guide member.

3. Apparatus for removing and replacing a cathode of an electrical discharge tube having a sealed housing comprising, a spherical-shaped casing, a socket carried by the casing sealed with respect to said housing, a solid ball fitting tightly within said casing, said ball having an opening therethrough normally aligned with said socket, 5 a guide member secured to said ball and extending therefrom in alignment with said opening, a cathode supporting rod fitting within said guide member and movable therein, a second socket carried by said casing arranged at an angle with 10 respect to the first socket, said casing having a slot therein for permitting swinging movement of said guide member, and a resilient member sealing said casing with respect to said guide member.
